UNITED STATES PATENT OFFICE.

GEORGE T. FULLER, OF BROOKLYN, NEW YORK, ASSIGNEE TO DUBOIS WATCH CASE COMPANY, OF BROOKLYN, NEW YORK, A CORPORATION OF NEW YORK.

SECURING DEVICE FOR LOOPED STRAPS.

1,323,359.

Specification of Letters Patent.

Patented Dec. 2, 1919.

Application filed February 1, 1919. Serial No. 274,421.

To all whom it may concern:
Be it known that I, GEORGE T. FULLER, a citizen of the United States, residing in the borough of Brooklyn of the city of New York, in the State of New York, have invented certain new and useful Improvements in Securing Devices for Looped Straps, of which the following is a specification, reference being had to the accompanying drawing, forming a part hereof.

This invention has for its object to provide an improved device for the ready attachment and detachment of looped straps, such as are commonly employed in securing wrist watches upon the wrists of wearers. Such straps are commonly made with or are made to form a loop to receive a straight bar which forms a part of the watch itself or of the clip which serves for the adjustment of the length of the strap. To permit the engagement of such a looped strap with such a bar, either the bar itself has been pivoted at one end and provided at the other end with a fastening device, which construction is liable to accidental release of the strap, or the strap is provided at one end with a flat eye through which the other part of the strap is drawn after it has been passed about the bar, the flat eye being then drawn up close to the bar, which arrangement is clumsy and undesirable because it involves several thicknesses of the strap in close proximity to the bar. By this invention provision is made whereby the objections to both of these arrangements are overcome, the strap is easily engaged with the bar, accidental disengagement is impossible, and the necessary strength is retained. The invention will be more fully explained hereinafter with reference to the accompanying drawing in which it is illustrated, and in which—

Figure 1 is a view in elevation of a wrist watch provided with the improved securing device, the strap being shown partly in section.

Fig. 2 is a detail view on a larger scale, partly in section.

Fig. 3 is a detail view of the watch as seen from the right hand in Fig. 1, partly broken out, the manner of introducing the strap being indicated by dotted lines.

Figs. 4 and 5 are detail views, partly in section, showing a modification of the device.

Figs. 6 and 7 are views illustrating the application of the invention to a clip for a 55 wrist strap.

In Figs. 1-5, the watch *a*, which may be of ordinary construction, is shown as having at opposite sides a tubular bar *b*, *b'* secured to the watch by arms *b*². Either or both of the tubular bars *b*, *b'* might be adapted for the ready attachment or detachment of the wrist strap *c*, but in the drawing only one of such bars is so shown. For this purpose the bar *b* is formed with a gap *b*³, which is sufficiently wide to permit the fabric of the strap to be slipped through it, and is preferably disposed obliquely to the axis of the tubular bar *b*. The loop of the strap to be engaged with the watch is slipped upon one of the members of the tubular bar *b*, as shown in Fig. 3, and is crowded over upon that member until the other edge of the strap clears the gap when it is allowed to slip back upon the other member of the 75 tubular bar. To prevent the possibility of accidental disengagement of the strap from the bar *b* and also to stiffen the bar so that it will not be likely to be bent out of place if a strain is put upon the strap, the tubular bar is provided, as shown in Figs. 2-3, with a pin *d* provided with a suitable knob *d'*, a friction enlargement *d*², which co-operates with a slightly inturned shoulder *b*⁴ so as to prevent accidental slipping out of the 85 pin, and with a head *d*³ which fits closely within the bore of the tubular bar *b*, and, by its engagement with the shoulder *b*⁴, prevents the complete removal of the pin. When the pin *d* is pulled out, as shown in Fig. 3, 90 the strap can be readily connected with or disconnected from the bar, but when the pin is in the position shown in Figs. 1 and 2 the gap *b*³ is closed thereby so as to prevent the disengagement of the strap from the 95 bar, the pin also serving to prevent excessive springing or bending of either member of the bar should a strain be put upon the strap.

In the construction shown in Figs. 4 and 100 5 the pin *d*⁴ is seated in the longer member of the tubular bar *b* against a spring *d*⁵ and is provided with a finger piece *d*⁶ which travels in a slot indicated by dotted lines at *b*⁶. Normally the pin *d*⁴ is pressed forward 105 by the spring *d*⁵ so as to close the gap *b*³,

but by the application of the finger nail or a suitable implement to the lug d^o the pin can be drawn back to open the gap.

In the construction shown in Figs. 6 and 5 7 the device is constructed as shown in Figs. 1, 2 and 3 and is applied to a clip e , such as is commonly employed with a strap for a wrist watch.

Various other embodiments and applications of the invention will readily suggest themselves.

I claim as my invention:

1. A securing device for a looped strap comprising a fixed, rigid bar having a gap 15 between its ends, means to support the members of the bar in fixed relation and means to close the gap.

2. A securing device for a looped strap comprising a fixed, rigid, tubular bar having a gap between its ends, means to support the members of the bar in fixed relation and a pin arranged to slide in the tubular bar to close the gap. 20

3. A securing device for a looped strap comprising a fixed, rigid, tubular bar having a gap between its ends, means to support the members of the bar in fixed relation, a pin arranged to slide in the tubular bar to close the gap and means to prevent the complete withdrawal of the pin. 25

This specification signed this 27th day of January, A. D. 1919.

GEORGE T. FULLER.
